ELECTRIC APPARATUS FOR DECOMPOSING
LIQUIDS AND ITS USE AS A GASOLINE
ECONOMIZER

Raymond H. P. Devaux, Tangier, Tangier

Application August 11, 1949, Serial No. 109,798
In France March 22, 1949

11 Claims. (Cl. 123—25)

1

The present invention relates to an apparatus for continuously decomposing or dissociating liquids which are a combination of elements, and more particularly water, with the help of an electric spark acting upon fine globules of atomized liquid. It may be applied in all apparatuses generally using a gaseous or atomized fuel, and more particularly for feeding all types of internal combustion engines and reaction jet engines in which it gives an appreciably increased efficiency or, which is the same, enables, for a same power provided by the engine, to reduce in a very important way the fuel consumption, and more particularly the gasoline consumption.

It has already been tried to inject or vaporize water in the fuel mixture of internal combustion engines in order to improve the combustion of the mixture. However, in spite of its advantages, this process has been given up because of the corosions and oxidations which are produced by the fuel mixture, particularly on the valves and cylinder-heads.

It has also been tried to ionize the fuel mixtures or the components (air and fuel) of these mixtures either through high frequency electric discharges, either through vacuum-tubes or apparatuses generating ultraviolet rays.

Finally it has also been suggested to ozonize the oxygen of the air which is a part of the fuel mixture in order to improve the combustion of this mixture in the engine, and to reduce the losses through unburnt fuel, consequently to increase the efficiency.

The various known apparatuses using the ionizing and ozonizing processes are costly, fragile and practically ineffective, because they are generally provided for a rated load of the engine and cannot follow the variations of the load by means of a corresponding adjustment of ionizing or ozonizing. In fact, in these apparatuses the production of sparks or the intensity of the electric discharges is constant, while the volume of the mixture or gas which passes through the apparatuses varies as a function of the load of the engine.

An object of this invention is to provide a process and an apparatus enabling to break up into its components a liquid maintained in suspension as fine globules in a gas, for instance water in suspension in air, by means of electric sparks, the latter being produced as a function of the gas flow passing through the apparatus in such a manner that the composition of the mixture at the outlet is substantially

2

constant. Another object is to provide an apparatus for decomposing liquids maintained in suspension as fine globules in a gas, for instance water in suspension in air, by means of electric sparks flying in the mixture of gas and liquid globules, said device adjusting automatically the number of sparks to the volume of liquid to be decomposed. When the apparatus is used for feeding an engine and when the broken up liquid is water, no oxidizing corrosion of the engine parts in contact with the fuel mixture containing the water injected through the apparatus is observed, which seems to prove that the apparatus has entirely broken up the water introduced into the mixture.

A further object is to provide a spark gap for producing electric sparks flying in a fluid flow passing through said spark gap, in which the number of sparks is self-adjusting to the volume of fluid of said flow.

According to the invention, the apparatus comprises a jet for atomizing the liquid, located in such a way that the globules of that liquid maintained in suspension in the gas flow are carried along towards a spark gap comprising one or more stationary electrodes and at least one rotary electrode rotating in front of the stationary electrode or electrodes, at a speed substantially in direct ratio with that of the gas flow, said electrodes being connected to a high voltage source, the distance between the stationary electrodes and the rotary electrode or electrodes being such that a spark flies between them when the rotary electrode passes in front of one stationary electrode.

The rotating electrode may be conveniently the metal rotor of an air-screw fan rotating the axis of a cylinder, through which passes the gas maintaining the liquid in suspension and 40 rotatively driving said rotor, the inclination of the blades of the latter determining the rotation direction and speed of said air-screw for a known speed of the gas flow corresponding to a predetermined suction at the end of the cylinder.

In the present description and claims the term "rotor of an air-screw fan" will be designated by "air-screw."

The number of sparks flying between the rotating electrode and the stationary electrodes, sparks which perform the decomposition of the liquid globules, is a function of the number of times the rotating electrode passes in front of the stationary electrodes, that is of the rotation speed of that electrode, which is main-

tained substantially in direct ratio with the speed of the gas flow, that is with the volume of gas passing through the apparatus. Consequently when the apparatus is adjusted for a predetermined rate of working it is substantially adjusted for all rates of working and its efficiency is about constant.

The electric insulation of the apparatus will be made in such a manner that no explosive difference of potential may occur at any moment at any other point besides the points located between the electrodes of the spark gap, and the leakage lines of the insulating materials will be such that the sparks will fly only at the predetermined points.

The gases produced by the decomposition of the liquid, that is hydrogen and oxygen in the case of water, are diffused in the gas flow as soon as they are produced and carried along in the fuel mixture whose quality is thus improved. Besides, a small quantity of ozone may be simultaneously produced because of the electric silent discharges which occur when the distance between the rotating electrode and the stationary electrodes exceeds the explosive distance. This ozone is also produced in direct ratio with the gas flow passing through the apparatus in such a manner that such ratio is substantially constant, which ensures a proper analysis of the fuel mixture at all working rates of the engine.

The apparatus may be located at any point of the inlet-tubing, either up-stream or down-stream with respect to the carburetor or mixer, or before or after the compressor or supercharger if the considered engine comprises one of these devices, a pipe connecting the atomizing jet to the tank containing the liquid.

It will be preferable to provide an anti-flame device before or after the spark gap, or simultaneously at both these locations, in order to prevent the fuel gas from igniting through the sparks flying between the electrodes of the spark gap.

It will be convenient to make the anti-flame device with metal parallel plates, which will be near enough to prevent the propagation of a flame, and these conducting plates may be alternately insulated to form two armature condensers on which may be applied a difference of potential substantially lower than that making the sparks fly. This device is not only an excellent anti-flame device but also an electrostatic precipitator which is able to retain the liquid globules which are not dissociated or gasified.

The spark gap may be fed by means of any source of electric high tension current, for instance, on an automobile, by means of an induction coil fed through the battery and having a proper breaker or buzzer inserted.

In an improved embodiment of the invention, the electric circuit producing the sparks is fed by two sources having different voltages, one having a higher voltage than the other but only capable of supplying, at all rates of working, a current of small magnitude in view of producing a spark between the electrodes of the spark gap, the other having a lower voltage but capable of producing, above a certain speed of the engine, a spark of a higher current magnitude in the gases ionised by the first spark, and consequently capable to achieve a more complete decomposition of the liquid. It will be convenient to form these two sources of electric current by means of two separate coils of a transformer and, in order not to discharge the battery too rapidly the current

necessary for feeding said transformer will come direct from the dynamo. In that way, at the low rates of working, when the voltage given by the dynamo is not sufficient for attracting the armature of the cut-out switch and charging the battery, the necessary energy will be provided only by the dynamo. Furthermore, the energy used for decomposing the liquid will be thus a function of the voltage of the dynamo, consequently of the speed of the gas flow sucked in by the engine.

In order to obtain a proper delivery of the liquid to the atomizer, a pipe may be provided for putting under pressure the tank which contains the liquid, for instance by using the exhaust gas a part of which is thus recycled. Advantageously this pipe may be arranged so that the pressure in the tank falls under the atmospheric pressure in case of a sudden fall of the speed of the engine, the liquid being then immediately sucked into the tank. For that purpose, the atomizer may comprise an appropriate nozzle, set perpendicular to the atomizing jet, receiving the exhaust gas by means of a branched pipe connected to the pipe transferring the exhaust pressure to the tank of liquid.

Finally, in order to avoid the apparatus being flooded in case of an untimely flow of liquid, a slope will be provided in the apparatus so as to carry along towards the outside the liquid which could spill.

When mounting an apparatus according to the invention on an already existing engine, it is observed that the power of the latter is much improved. It is of course possible to avoid change of the initial power of the considered engine through reducing the cross-section of the nozzle of the fuel outlet (jet) while keeping an optimum cross-section at the air inlet (choke). For the same power and with the apparatus according to the invention, a very important decrease, which may reach 50% of the fuel consumption, may be obtained with an additional consumption of water.

Other objects and advantages of the invention will be apparent during the course of the following description. In the accompanying drawing forming a part of this application and in which like numerals are employed to designate like parts throughout the same,

Figure 1 is a longitudinal section of an embodiment of the apparatus.

Figure 2 is a vertical section taken on line II-II of Figure 4.

Figure 3 is a transverse section taken on line III-III of Figure 1.

Figure 4 is a detailed view of Figure 1 showing on a higher scale the arrangement of the spark gap and atomizing nozzle.

Figure 5 is a diagram of the electric circuits of an apparatus using two voltages.

Figure 6 is a plan view of an arrangement of the electrodes of a spark gap using two voltages, the air-screw being shown in section.

Figure 7 is a diagram showing the arrangement of the pipes connecting the tank of liquid to the apparatus and to the exhaust pipe of the engine.

Figure 8 is a longitudinal vertical section of a modification of the inside arrangement of the apparatus,

Figure 9 is a vertical section of the connection enabling to connect the pipes of the apparatus to the exhaust of the engine.

In the embodiment shown in the drawing, the apparatus comprises a device 1 for dissociating

a liquid mounted in a horizontal chamber 1_b provided with a flange 2 enabling to secure the apparatus immediately to the air intake of the carburetor, in place of the conventional air filter of an internal combustion engine or at the intake of an air-supercharger in the case of a direct injection engine or a reaction jet engine.

The chamber 1_b is connected, through a slanting duct 3 which progressively widens out, to a filtrating device of any type. In the drawing there is shown a filter automatically carrying the dust away, made of consecutive rows of little plates having the shape of troughs 4 slanting in the direction of the air passing through (shown by arrow F) and arranged to form baffles (Figure 3). The ends of the troughs 4 pass slightly beyond the lower wall of the air inlet choke-tube 5 which has such a transverse section that the losses of head resulting from the troughs do not exceed at full rate a predetermined value.

The lower wall of the horizontal chamber 1_b is made of an insulating plate 1_a which supports a cylinder tunnel or tube 6 of insulating material provided at the front and at the rear with deflectors 6_a and 6_b for leading into the cylinder a part of the air flow sucked by the engine and sending to the rear side of chamber 1_b the mixture of air and decomposed liquid.

Inside cylinder 6 there is disposed the liquid atomizer made of a vertical tube 7 secured to the plate 1_a whose upper end is provided with a small diameter jet 8 substantially located in the axis of cylinder 6. The tube 7 is connected through a pipe (not shown) to the tank containing the liquid to be decomposed which is located at a proper altitude. The atomizing of the liquid is made in the known way by means of the underpressure produced in the jet through the passage of the aspiring air stream which passes through the tunnel 6, and the globules of liquid form an atomizing cone shown with dots and dashes in Figure 4 having as an apex the jet 8.

The shaft of the air-screw 9 which forms the rotating electrode of the spark gap is mounted along the axis of cylinder 6 and this air-screw is set in such a manner that its transverse medial plane is substantially merged with the plane of the base of the atomizing cone (Figure 4). The air-screw 9 freely rotates on its shaft 10 maintained by any suitable means in an insulating seat 11 and said shaft is electrically connected to a terminal 12 secured to the insulating plate 1_a. Metal studs 13, 14, 15 and 16 (Figure 2) made of nickel for instance, are secured to the internal wall of cylinder 6 or conveniently sunk into that wall so as to be flush with the inside surface, in such a manner that their axes are located in the transverse medial plane of air-screw 9. They are all electrically connected to a terminal 17 also secured to plate 1_a.

Downstream with respect to the cylinder tunnel 6 is the anti-flame device made of parallel, metal plates 18, 19 which are near enough to prevent a flame ignited on one side of the device passing on the other side but allow the air and the gases issuing from the dissociated water freely to pass. As it is shown in Figure 1, the even plates 18 will be conveniently insulated and electrically connected to a terminal 20, and the odd plates 19 grounded. When applying a suitable tension between the earth and the terminal 20, the anti-flame device will then act as an electrostatic precipitator, and complete the action of the precipitator troughs 4, so that the air and gas entering the carburetor are perfectly cleaned.

The operation of this apparatus is as follows:

A sufficient voltage is applied between the insulated terminals 12 and 17, for instance through connecting these terminals by means of insulated wires 21 and 22 to the two poles of a high voltage induction coil distinct from the ignition coil and the gas flow is generated for instance through starting the engine, in such a manner that air-screw 9 rotates at a speed which is a function of the speed of said gas flow. When the screw blades are in front of studs 13 to 16, a spark flies between each one of these studs and the edge of the corresponding blade, but when this blade has passed beyond this stud and is not still in front of the following stud, the distance separating the electrodes having different polarities is too great and no spark flies. Consequently the number of sparks which may fly between the distinct electrodes is a function of the rotation speed 20 of air-screw 9 which itself is a function of the speed of the gas flow and thus of the working rate of the engine.

The suction produced through the engine in the cylinder 6 which produces, through the jet 8, the atomizing of the water to be decomposed, is also a function of the working rate of the engine, in such a manner that the flow of atomized water and the number of sparks produced for decomposing that water follow automatically the present needs while remaining in a ratio which does not vary much.

The globules of water which are submitted to the centrifugal forces generated by the fast rotation of the screw are hurled towards the periphery of cylinder 6 and almost all of them are included in the gaseous flow submitted to the action of the sparks, which ensures a proper decomposition of the liquid. The produced gases, hydrogen and oxygen, are swiftly carried 40 along through the air current which passes through the cylinder tunnel 6 and are spread in the mass of air without being able to be recombined under the action of the sparks. These gases having a high explosive power, are thus included in the air sucked in by the carburetor and their mixture with said air considerably improves the calorific power of the gaseous mixture. The resulting increase of the engine efficiency makes it possible to reduce the proportioning of the fuel mixture through a decrease of the section of the main jet, while keeping the same power provided by the engine. As a result, the gasoline saving may be as high as 50%, the power necessary for the production of sparks being provided by the usual battery, that is to say by the engine itself.

In Figure 5, the electric circuit of an apparatus having two different high voltage sources has been diagrammatically shown, this circuit being fed by the dynamo 25 which is provided for charging the battery 26 and comprising a cut-out switch 27. The primary 28 of the transformer is connected to the dynamo at 25a before the cut-out switch 27, in such a manner that the battery is not used for the working of the apparatus, an appropriate contact-breaker 29 providing the fast breaks which are necessary. One of the secondary coils 30 of the transformer provides, at the low revolution speeds, a high voltage and a low current for instance 15,000 volts and 1 to 2 milliamperes, while the other secondary coil 31 of the transformer, having heavier wires, is capable of supplying at full rate a current of several milli-amperes with a lower voltage, 5000 volts for instance. The above

values are not absolute and are only given in order fully to explain the used arrangement the characteristics of the apparatus being evidently a function of the spacing between the electrodes of the spark gap, that is between the screw 9 driven by the gaseous flow and the stationary studs, and of the power of the engine. The stationary studs are shorter than in the device shown in Figure 4 and above described, but their number is twice as great and they are arranged in sets of two at a small distance one from another. Assuming that the gas flow has the direction of the arrow F, the studs 32 of each set are connected to the high voltage secondary 30, while the studs 33 are electrically connected to the high current secondary 31.

It will be convenient to sink the studs 32, 33 in the insulating mass of the tunnel 6, in such a manner that they are flush with its inside wall. They are slightly angularly shifted according to 20 the inclination of the blades of screw 9, as it is shown in Figure 6. They are axially as near as possible one to another, but are still separated by such a distance that no spark can fly between them. In fact they are submitted to a difference 25 of potential equal to the difference between the voltages of coils 30, 31 which are both connected by their second terminal to screw 9.

At the low rates of working the quantity of atomized water is small and the sparks of low 30 current which fly between the screw and the studs 32 are sufficient for achieving the decomposition. When the speed of the engine increases the voltage of the dynamo increases and the voltage developed in the secondary coil also 35 increases. The sparks produced by the high voltage coil 30 between the studs 32 and screw 9 are blown by the gaseous flow which is thus ionized between the studs 33 and the screw. Above a certain speed of revolution, the voltage 40 given by the secondary 31 is sufficient for causing a high current spark to fly between 9 and 33 in the ionized gases. The decomposition of the liquid, a larger quantity of which is atomized, is thus more complete.

The apparatus also enables the recovery without difficulty of the oil vapours which escape through the ports provided for filling up the engine. Each time it has been tried to make such a recovery, the result has been the sooting 50 of plugs and cylinder heads which required to stop the engine for cleaning. The apparatus enables this recovery without any drawback. It is enough to connect the ports through which the oil vapours escape to a point located upstream with respect to the device ensuring the decomposition of the liquids, or immediately at the inlet of the carburettor. It is then observed, what was unexpected in that case from the results obtained with the known apparatuses, that 55 no sootting occurs even after a long period of working having strongly heated the oil.

The spark gap having the shape of an air-screw driven at a variable speed by an air current could be used for other purposes than the 60 decomposing of liquid globules through an electric spark. It is in fact a kind of distributor rotating as a function of the speed of a circulating fluid and could be used for feeding any other electric device. It is here stated that this 65 spark gap itself is a part of the invention and that the various uses which might be made thereof do not depart from the scope of the said invention. For instance it would be possible slightly to increase the distance between the 70

stationary and movable electrodes in such a manner that the sparks cannot fly, but that silent discharges are generated when the screw blades pass in front of the stationary studs. Thus an ozonizer would be made giving substantially a constant ratio ozone/air, in spite of the important variations of the air flow passing through the apparatus.

The apparatus according to the invention which makes the decomposing through an electric spark of any finely atomized liquids and more particularly of water, when it is mounted on the feed of internal combustion engines, ensures a better and more complete combustion of the hydrocarbons with, as result, a very important improvement of the efficiency of the engine and the disappearance of the sootting through carbonization, as a consequence of an incomplete combustion.

In case the device would be mounted on an automobile vehicle, and consequently submitted to the jerky action of the road producing variations of the level of the liquid in the tank, variations which may cause the atomizer to be unprimed, it would be possible to provide in that tank a slight pressure, obtained for instance by means of a pipe connected at one end to the tank, above the level of the liquid, and at the other end to any point of the exhaust pipe. Because of this arrangement there is pressure in the tank only when the engine works, and when the vehicle is stopped no leak of liquid will occur. It is convenient to cool the gas intake which may be made by a ribbed member having a fine hole connected to the end of the pipe going to the liquid tank.

When the above mentioned tank is put under pressure by the exhaust gas, and the rate of working of the engine suddenly slows down, for instance when the accelerator is released, the exhaust pressure is reduced but the pressure in the water tank is reduced much less, consequently the liquid which still flows to the atomizer and which is no longer aspirated may flow into the apparatus which may be flooded thereby if no precaution is taken.

It is possible to cope with the above difficulties with the help of the device shown in Figure 7. In this device the atomizing is achieved by means of the combined jet 8 and nozzle 34, mounted along the axis of tunnel 6 at a small distance from the jet 8, and connected to the exhaust pipe 35 by means of a pipe 36. The pipe 37 which puts the liquid tank 38 under pressure is branched on pipe 36, while the jet 8 is fed with liquid by the pipe 39. With said device the unburned fuel, present in the exhaust gas used for atomizing the liquid, is recycled to the intake of the engine thus causing a further reduction of the fuel consumption.

It will be convenient to use for connecting the pipes 36 and 37 the connection 40 shown in Figure 9 which comprises cooling ribs 41 and two connections at right angles 42 and 43. This connection is screwed into the wall of the exhaust pipe 35 and enables the connection to be made by drilling only one hole in exhaust pipe 35.

The operation of the device is as follows: Assuming the engine runs at a high rate, the pressure in the pipe 35 is transferred above the liquid of tank 38 by means of the pipe 37. A gaseous flow at high speed is started at the outlet of nozzle 34 and the liquid delivered by the pipe 39 to jet 8 is atomized in the apparatus. When the rate of the engine slows down suddenly, the pressure immediately slows down in the pipe 36, be-

cause of the decrease of the pressure at 35 and of the slight suction produced by nozzle 34 immersed in a low speed gaseous flow. This suction is transferred up to tank 38 by the pipe 37, so that the liquid contained in the pipe 39 is sucked into the tank.

If it is desired, and in order to avoid the flooding of the apparatus in case of leaks of liquid, means for carrying away this liquid to the outside may be provided. For instance an appropriate basin having an outlet pipe may be designed. Another means consists in downwardly inclining a part 1c of the lower wall in the upstream direction as shown in Figure 8, and providing at the lower part a hole in the wall of chamber 4. An exit pipe 44 may be secured in that hole and said pipe may be curved towards the rear for carrying the liquid away.

It is to be understood that the form of my invention herewith shown and described is to be taken as a preferred example of the same and that various changes in the shape, size and arrangement of parts may be resorted to without departing from the scope of the subjoined claims. It would be more particularly possible to provide several rotating electrodes mounted end to end each one being associated with stationary electrodes, and to bend the blades of the distinct electrodes in opposite directions in order to give each air-screw a different direction of revolution improving the mixture of the gases. It is also obvious that for the screw of the spark gap could be substituted any other electrode rotating at a speed in direct ratio to that of the gas flow.

I claim:

1. A spark gap for producing electric sparks as a function of the volume of a fluid flow passing through said spark gap which comprises two high voltage sources, the first one having a higher voltage than the second, and said second source being capable of supplying a higher current than the said first one source; at least one electrode connected to said high voltage sources, said electrode made of an air-screw arranged and adapted to be freely, rotatively driven through said fluid flow; and at least two stationary electrodes insulated from one another, angularly shifted according to the inclination of the blades of said air-screw and connected to said high voltage sources.

2. In a process for decomposing water carried along in the air flow sucked in by an internal combustion engine the steps of withdrawing a fraction of the exhaust gas flowing from said engine, atomizing water by means of said fraction of exhaust gas to form fine liquid globules, injecting said globules into the air flow sucked in by said engine, and submitting said globules to the action of electric sparks flying in said air flow, the number of said electric sparks being in direct ratio with the speed of said air flow, whereby the unburned fuel present in said fraction of exhaust gas is recycled to the intake of said engine.

3. In an apparatus for decomposing in a gaseous flow, whatever be the rate of delivery of said flow, substantially an even proportion of a liquid formed of a combination of elements and contained in a suitable tank, the combination of an atomizer and a high voltage spark gap, said atomizer comprising a tube of insulating material through which the gaseous current flows and a small diameter jet connected to said liquid tank and radially disposed in said tube with its orifice on the axis of said tube; said high voltage spark gap being arranged down-stream with respect to

said atomizer and comprising, at least one high voltage source, a rotating electrode made of a metal air-screw freely rotating around a shaft coaxial with said tube, and at least one stationary electrode secured on the inner wall of said tube, in front of said air-screw and radially spaced from the ends of the blades of said air-screw a distance at most equal to the sparking distance corresponding to the voltage of said source and electric connections for connecting said both electrodes to said high voltage source, whereby the gaseous flow causes atomizing of the liquid as a function of its speed, rotation of said air-screw at a speed substantially in direct ratio with its own, and the flying between said electrodes of a number of sparks adjusting itself to the rate of delivery of said flow.

4. In an apparatus for decomposing in a gaseous flow, whatever be the rate of delivery of said flow, substantially an even proportion of a liquid formed of a combination of elements and contained in a suitable tank, the combination of an atomizer and a high voltage spark gap, said atomizer comprising a tube of insulating material through which the gaseous current flows and a small diameter jet connected to said liquid tank and radially disposed in said tube with its orifice on the axis of said tube; said high voltage spark gap being arranged down-stream with respect to said atomizer and comprising two high voltage sources of energy, the first one having a higher voltage than the second, and said second source of energy being capable of supplying a higher current than the first one, a rotating electrode made of a metal air-screw freely rotating around a shaft coaxial with said tube, said metal air-screw being connected to one terminal of each of said sources of energy, and at least two stationary electrodes secured a short distance one before the other with respect to the direction of said gaseous flow on the inner wall of said tube, both in front of said metal air-screw, and radially spaced from the ends of the blades of said air-screw a distance at most equal to the spark distance corresponding to the voltage of said first source of energy, the first of said stationary electrodes, closer to said atomizer, being connected to the first source of energy having the higher voltage, and the second of said stationary electrodes, remote from said atomizer being connected to the second source of energy capable of supplying the higher current; whereby said gaseous flow causes atomizing of said liquid and rotation of said air-screw, and when a blade of said air-screw comes opposite to said stationary electrodes, a spark flies between said blade and said first stationary electrode, ionizing the gas and causing flying of a higher current spark between said blade and said second stationary electrode.

5. In an apparatus as claimed in claim 4 a pair of stationary electrodes secured in front of said air-screw a short distance one before the other with respect to the direction of said gaseous flow, flush with the inner wall of said tube and angularly shifted according to the inclination of the blades of said air-screw.

6. In an apparatus as claimed in claim 3 the disposition which consists in locating the radially disposed jet of the liquid atomizer at such a distance from the spark gap that the vaporization cone of the liquid fed to this jet impinges the inner wall of said tube in a plane intersecting said air-screw.

7. An apparatus according to claim 3 adapted to feed partially an engine with the break-up components of water constituting the liquid in

the liquid tank, in which said tube is inserted in the air intake pipe of the engine, said atomizer further comprising a nozzle arranged along the axis of said tube up stream with respect to said jet connected to said liquid tank, and a pipe connecting said nozzle to the exhaust pipe of said engine, whereby a portion of the exhaust gas is used for atomizing the water.

8. An apparatus according to claim 3 adapted to feed partially an engine with the break-up components of water constituting the liquid in the liquid tank, in which said tube is inserted in the air intake pipe of the engine, said atomizer further comprising a nozzle arranged along the axis of said tube up stream with respect to said jet connected to said liquid tank, a first pipe connecting said nozzle to the exhaust pipe of said engine, and a second pipe branched to said first pipe connected to said water tank.

9. An apparatus according to claim 3 adapted to feed partially an engine with the break-up components of water constituting the liquid in the liquid tank, in which said tube is inserted in the air intake pipe of the engine, said atomizer further comprising a nozzle arranged along the axis of said tube up stream with respect to said jet connected to said liquid tank, a first pipe connecting said nozzle to the exhaust pipe of said engine, a second pipe branched to said first pipe connected to said liquid tank, and a ribbed connection screwed in the wall of the exhaust pipe of said engine having two tubings at right angles one with respect to the other for feeding said first and second pipes.

10. An apparatus according to claim 3, adapted to feed partially an engine with the break-up components of water constituting the liquid in the liquid tank, in which said tube is inserted in the air intake pipe horizontally disposed of the engine, said tube having at least a portion of its wall slightly inclined with respect to the horizontal and being provided at its lower part with a port, and a pipe connected thereto for carrying away water leaking from said jet.

11. A fuel economizer for an engine, capable of feeding said engine with substantially an even proportion of detonating gas obtained by decomposition in a gaseous flow of an even proportion of water sucked in a suitable tank and atomized in said gaseous flow whatever be the rate of delivery of said flow, comprising in combination an atomizer and a high voltage spark gap, said atomizer comprising a tube of insulating material through which the gaseous current flows and a small diameter jet connected to said tank and radially disposed in said tube with its orifice on the axis of said tube; said high voltage spark gap being arranged down-stream with respect to said atomizer and comprising, at least one high voltage source, a rotating electrode made of a metal air-screw freely rotating around a shaft coaxial with said tube, and at least one stationary electrode secured on the inner wall of said tube, in front of said air-screw and radially spaced from the ends of the blades of said air-screw a distance at most equal to the sparking distance corresponding to the voltage of said source, and electric connections for connecting said both electrodes to said high voltage source, whereby the gaseous flow causes sucking and atomizing of said water as a function of its speed, rotation of said air-screw at a speed substantially in direct ratio with its own, and the discharge between said electrodes of a number of sparks adjusting itself to the rate of delivery of said flow.

RAYMOND H. P. DEVAUX.
